UNITED STATES PATENT OFFICE.

CARL WEBER, OF CHICAGO, ILLINOIS.

STRUCTURAL METAL BAR.

No. 832,711.

Specification of Letters Patent.

Patented Oct. 9, 1906.

Application filed September 1, 1905. Serial No. 276,707.

To all whom it may concern:

Be it known that I, CARL WEBER, a citizen of the United States, residing at Chicago, in the county of Cook and State of Illinois, have 5 invented a new and useful Improvement in Structural Metal Bars, of which the following is a specification.

My invention relates to an improvement in the class of metal bars employed as the reinforcing medium in reinforced concrete structures by embedding them in the concrete in the procedure of erecting such structures for the primary purpose of rendering the concrete elastic by combining its high compressive strength with the high tensile strength of the steel.

In structures of the kind referred to it is the recognized principle that the two materials employed—namely, steel and concrete—20 which expand and contract correspondingly, or approximately so, under the influence of temperature, form at their contacting surfaces an intimate union of a chemical, as well as a mechanical, nature, whereby a strong cohesion of the materials ensues and the steel 25 is protected against oxidation. Under the tension strains to which the structure is subjected its safety depends in a large measure upon the extent of cohesive bonding of the 30 two materials, so that it is an object to provide on the metal bars the greatest possible surface area for presentation to the concrete. The ordinary T-bar hitherto most commonly employed, while it gives satisfactory results 35 in the direction referred to, is difficult to place properly in positioning it, especially in heavy girder construction where exact location of the reinforcing members is of primary importance, and, besides, it is difficult without 40 special bending-machines for the purpose, which, moreover, are rarely at hand where a structure is being erected to bend properly a T-bar, since owing to its unsymmetric cross-section the neutral axis changes whenever 45 the slightest twist in the bar occurs, and this requires a larger factor of safety to be considered in the construction than would otherwise be necessary. My improvement overcomes these difficulties by affording a bar 50 having a symmetric cross-section, and yet presenting to the concrete the greatest possible surface area.

Referring to the accompanying drawings, Figure 1 is a view in perspective of my im- 55 proved bar, and Fig. 2 a section taken at the

line 2 on Fig. 1 and viewed in the direction of the arrow.

A is my improved steel bar for embedment in the concrete in metal-reinforced concrete structures, comprising a central longitudinal body portion a and four wings a' , radiating from it preferably at right angles to each other, thus forming between adjacent wings the longitudinal transversely-curved grooves a^2 . The area of the cross-section of the central body portion of the bar is greater than the cross-sectional area of at least any two of the wings, thus insuring great tensile strength in the structure of which it becomes a part. At intervals along the bar sections of the metal of two oppositely-positioned wings are upset, thus thickening those wing-sections and forming at intervals therein longitudinal recesses b , which are beveled at their ends and widened at their bases, as shown, the metal in the upsetting operation spreading beyond the edges of the wings and forming shoulders b' .

By providing the bar with a thickened central body portion and four radiating wings, as described, great tensile strength is insured in the concrete structure of which it becomes a part, and large surfaces are provided on the bar for contact with the concrete, and still greater surface area is presented for contact with the concrete by the recesses and shoulders of the wings, which materially augment the surface area for presentation to the concrete and form depressions by which additionally secure interlocking of the mass of concrete and the bar embedded therein is afforded.

What I claim as new, and desire to secure by Letters Patent, is—

As a new article of manufacture, a reinforcing-bar for metal-concrete construction, consisting of a metal bar having longitudinal wings with the spaces between adjacent wings concavely curved in cross-section, and longitudinal recesses at intervals in opposite wings having their bases expanded laterally and forming abrupt end shoulders projecting beyond the adjacent surfaces of the unrecessed portions of the wings in which said recesses are formed.

CARL WEBER.
